PRINTING INSTRUMENTALITIES FOR
TYPEWRITING MACHINES

Frank H. Trego, New York, N. Y., assignor, by
mesne assignments, to Ralph C. Coxhead Cor-
poration, New York, N. Y., a corporation of
Delaware

Application February 4, 1931. Serial No. 513,270

25 Claims. (Cl. 197—49)

This invention relates to printing instrumen-
talities for typewriting machines and is in the
nature of improvements which may be used with
parts shown in my application, Serial No. 495,872,
5 filed November 15, 1930.

The invention is shown as applied to the ma-
chine known as the Varietyper in which there is
provided a type shuttle which may be rotated
through various angular distances, by the key-
10 levers, to select the desired type, subsequent to
which a hammer is operated to strike against the
shuttle to print on a work-sheet disposed between
the shuttle and the hammer, and in which ma-
chine the carriage assists in restoring the ham-
15 mer to normal.

An object of the present invention is to facil-
itate the operation of the machine. To this end
the printing hammer is restored to normal or
20 cocked by an electro-magnet, and the printing
operation of the hammer is effected by a spring
under the control of the keys.

A feature of the invention relates to means in-
dependent of the carriage and the escapement
mechanism, whereby the hammer is held cocked
25 against the action of its actuating spring.

Another feature of the invention relates to
means under the control of the keys whereby the
release of the hammer may be effected.

A further feature of the invention relates to
30 means, including a switch operable by the ham-
mer, to effect the energization of the electro-
magnet, to thereby restore the printing hammer
or, in other words, cock it.

Still another feature of the invention relates
35 to means to delay the closing of the switch un-
til the hammer has printed so as to prevent a
premature return of the hammer. This means
is also effective to delay the opening of the switch
so as to insure cocking of the hammer before the
40 electro-magnet, which returns the hammer, is
de-energized.

Other features and advantages will hereinafter
appear.

In the drawings which form part of the speci-
45 fication,

Fig. 1 is a sectional side view of the machine;

Fig. 2 is a sectional top plan view of a portion
of the machine taken on the line 2—2 of Fig. 1;

Fig. 3 is a rear view of the machine;

50 Fig. 4 is a skeleton side view showing the ham-
mer printing, and the actuation of the switch
initiated and about to be completed by the de-
tent;

55 Fig. 5 is a similar view showing the switch
closed;

Fig. 6 is a rear view showing the dog-rocker
of the escapement mechanism operated and the
hammer about to be released; and

Fig. 7 is a view similar to Fig. 6 but showing the
loose dog and the hammer operated. 60

Similar reference characters represent similar
parts throughout the several views.

The machine includes a main frame 20 pro-
vided with tracks 22 upon which is supported a
carriage 23, to travel back and forth, through the 65
medium of anti-friction balls or rollers 24. The
carriage is provided with feed rollers 25 and 26
by which a work-sheet 26^a may be fed upwardly
between a type carrier or shuttle 27 and a ham-
mer 28, the latter being located behind the work- 70
sheet.

The type shuttle 27 is located in front of the
work sheet and is supported on an anvil 30 se-
cured to a shaft 31 suitably supported by a cross-
bar 32 and a plate 33 on the machine frame. 75
The shuttle 27 is actuated by a lever 34 connected
to said shuttle by an upwardly extending finger
35 engaging a fin 36 which extends through a
slot 37 in the anvil 30, the fin serving also to
support the shuttle on the anvil. 80

The shuttle actuating lever 34 is secured to a
sleeve 38 rotatably supported on the shaft 31
and bearing on the cross bar 32. Said lever may
be actuated in opposite directions about the axis
of the shaft 31 in the usual manner by means 85
including two universal bars 40, one being asso-
ciated with the set of key-levers 41 to the right-
hand side of the machine, the other (not shown)
being associated with the set of key-levers to the
left-hand side of the machine. Each universal 90
bar 40 is operable by its associated key-levers to
actuate a frame 41, of which the universal bar
forms a part, about a fulcrum 42 to swing an
upwardly extending arm 43 rearwardly to actu-
ate the shuttle lever 34; a return spring 44 being 95
provided for the universal bar.

To assist in registering the selected types at
the printing point, indexing devices or stops 50
are associated with the key-levers 41, and actu-
able thereby against the action of return springs 100
51, to project the upper ends of the stops 50
into the path of an arm 52 of the shuttle actuat-
ing lever 34, said lever when actuated striking
the operated stop to arrest the type shuttle, with
the selected type at the printing point. 105

The carriage 23 is connected by the usual rack
55 with a pinion 56 of the carriage escapement
57 which is actuatable by a universal bar 58. The
universal bar 58 is engageable by the rear ends of
the key levers 41 and forms part of a frame 59 110

actuable about pivots 60 to swing downwardly a rearwardly extending arm 61 which operates a dog-rocker 62 (Fig. 3) about its pivot 63 to carry a fixed dog 64 into the path of the teeth 65 of an escapement wheel 66 secured to a shaft 67; the escapement wheel 66 having the usual one-way driving connection, with the carriage, including a spring-pressed pawl 68 (Fig. 2) on a disk 69 and a ratchet 70; the carriage being urged leftwardly 5 by a spring drum 71 (Fig. 2) which is connected to the carriage 23 by a strap 72.

After the dog 64 has moved into the path of the teeth 65 of the escapement wheel, a loose dog 75 is swung about its pivot 76 out of engagement with the escapement wheel (see Fig. 6) 15 by an arm 77 having a slot 78 into which extends a pin 79 from said loose dog. Upon the release of the loose dog it is carried upwardly as in Fig. 7 by a frame 80 pivotally supported on the escapement shaft 67, said frame being actuated by a spring 81. The pawl 75, as it is carried upwardly, is guided into the path of the next adjacent tooth of the escapement wheel, by the inclined slot 78, so that upon the subsequent release of 20 the escapement wheel from the dog 64, the escapement wheel rotates and thus returns the loose dog to normal, thus effecting a single letter feeding movement of the carriage.

The hammer 28 (Figs. 1 and 2) is secured to 30 a shaft 85 supported on the main frame 20 by pivot screws 86. It is held cocked against the action of a spring 87 by a pawl 88 (Fig. 3) engaging a projection 89 on the hammer. Upon the release of the hammer from said pawl 88, in a 35 manner hereinafter described, the spring 87 actuates it about the pivots 86 to strike against the shuttle 27.

In order to disengage the pawl 88 from the projection 89, when the hammer is to be operated, there is provided on the arm 61, of the escapement operating frame 59, an extension 90 which, upon the actuation of any one of the key levers 41, pulls downwardly a link 91 connected to an arm 92 secured to a shaft 93; the shaft 93 being supported on a bracket 94 secured to the main frame 20. The shaft 93 has secured thereto another arm 95 which is actuated, in a clockwise direction in Fig. 3, to swing the holding pawl 88 about its pivot 96, through the medium of an actuating pawl 97, pivotally supported on said arm 95, by a stud 98, as in Fig. 6, to release the hammer 28. Instantly after the release of the hammer from the pawl 88 the latter becomes released from the actuating pawl 97 and is snapped back 50 to normal position by a spring 99, as in Fig. 7, where the pawl 88 is arrested against the hammer projection 89.

The release of the pawl 88 from the actuating pawl 97 is effected so that the pawl 88 may be in 60 readiness to lock the hammer in its normal or cocked position should the hammer be restored (as hereinafter described) before the actuating pawl 97, since the return of the latter may be delayed by a slow removal of the finger from the 65 depressed key lever. The actuating pawl 97 in returning to re-engage the holding pawl, may yield against the action of a spring 99^a to snap behind a tooth 100 of the pawl 88. The spring 99^a tends to hold the actuating pawl against a 70 stop 101 by which its movement is limited relatively to the supporting arm 95.

The effective length of the link 91 may be 75 varied to effect proper co-operation of the actuating pawl 97 with the holding pawl 88. To this end there are provided nuts 102 and 103 threaded

on the link 91 and whereby the point of connection of said link with the extension 90 may be adjusted.

The hammer is returned or cocked, against the action of its spring 87, by an electro-magnet or solenoid 105, the coil 106 of which may be connected to a source of power by a manually controlled switch 107 so that when a switch 108 (Fig. 1) is closed by the hammer, as hereinafter described, an electric circuit is completed including a conductor 109, extending from the source of power, switch 107, coil 106, conductor 110, fixed contact 111 and movable contact 112 of switch 108, and conductor 113 which is also connected with the source of electric energy.

Upon the closing of the switch 108, which occurs after printing, the coil 106 is energized and it sucks in a plunger 114 to return the hammer from the position in Fig. 4 to the position in Fig. 1.

The connection between the plunger 114 and the hammer includes a lever 116, having a pin-and-slot connection 117, 118 with the plunger 114, whereby said plunger may actuate said lever about a stud 119 on a fixed bracket 120 which 100 may be secured to a flux frame 121 of the solenoid. The lever 116 draws forwardly a link 122 connected to an arm 123 secured to the hammer supporting shaft 85 to thus rock the latter and thereby return the hammer to normal where, it will be 105 remembered, the latch 88 engages the extension 89 to hold the hammer against the action of the spring 87.

The switch 108 includes an actuable element 125 pivotally supported by a stud 126 upon a fixed 110 bracket 127, and has mounted thereon, but suitably insulated therefrom, the switch contact 112. While the hammer is moving to its printing position an extension 128 thereon engages an arm 129 to operate the element 125 about its pivot to initiate the closing operation of the switch 108.

To guard against a premature return of the hammer 28, or, in other words, insure printing thereof, before the solenoid is energized to return said hammer, the operation of the switch 120 or controlling means 108 is retarded so that, although its operation has been started by the hammer, it is not completed until after the printing has occurred. For this purpose the arm 129 is pivotally supported, by means of a stud 130, on 125 the actuable element 125 of the switch; said arm 129 being actuable, when engaged by the hammer extension 128, about the pivot 130 and against the action of a spring 131, the actuation of the element 125 being resisted by a weight 132 and a 130 detent spring 133 having a roller 133^a engaging one side of a nose 134 formed on the element 125. While the spring 131 recovers and overcomes the inertia of the weight 132, the element 125 is further rotated thereby, about its pivot 126 135 (Fig. 4) to move the nose 134 to the lower side of the roller 133 whereupon the detent becomes effective to continue the actuation of the element 125 and thus close the switch, as in Fig. 5, where the hammer is printing and is just about to be 140 restored to normal by the solenoid 105 which, it will be remembered, is energized by the closing of the switch 108.

Similarly, provision is made to delay the opening of the switch or controlling means 108 so as 145 to insure latching of the hammer, against the action of its spring 87, before the solenoid is de-energized. As the hammer 28 returns, the extension 128 thereof actuates an arm 137 about a pivot 138 and against the action of the spring 150

131 to overcome the inertia of the weight 132. The return movement of the actuatable element 125 is thus initiated while the latching of the hammer is taking place, and when the latter 5 has been accomplished the detent 133, 133^a acts to complete the action of the switch element 125 and thus open the switch to de-energize the solenoid 105. The contact 112 of the switch 108 is supported by a resilient member 139 so that 10 the switch 108 may be kept closed for a time during the initial movement of the element 125 to open said switch.

The arms 129 and 137 are provided with set screws 140 and 141, respectively, whereby the 15 points of contact of the arms 129 and 137 may be adjusted relatively to the hammer extension 128 to assist in timing the operation of the switch.

The spring 131 is connected between the arms 20 129 and 137 and tends to draw their operable ends towards each other. They are arrested, however, by stops 142 and 143 on the actuatable element 125. The movement of said actuatable element 125 may be limited in both directions 25 by stops 144 and 145 on the bracket 127.

While certain preferred embodiments of the invention have been shown, it should be understood that changes in the form, arrangements, proportions, sizes and details thereof may be 30 made without departing from the scope of the invention as defined in the appended claims.

I claim:—

1. In a typewriting machine, the combination 35 of two co-operating elements, namely, a hammer and an anvil, a type shuttle associated with said elements, key-levers, a spring, means operable by said key-levers to render the spring effective to actuate one of said elements towards the other to print, an electro-magnet and means operable 40 by the key-levers whereby the electro-magnet is rendered effective to return the operated one of said printing elements to normal against the action of said spring.

2. In a typewriting machine, the combination 45 of two co-operating elements, namely, a hammer and an anvil, a type shuttle associated with said elements, key-levers, a spring under the control of said key-levers to actuate one of said elements towards the other to print, an electro-magnet to return the actuatable element, an electric circuit for said electro-magnet, and a normally open switch in said circuit operable by the actuatable element to close said switch to energize the electro-magnet to return the operable element.

55 3. In a typewriting machine, the combination of two co-operating elements, namely, a hammer and an anvil, a type shuttle associated with said elements, key levers, a spring under the control of said key-levers to actuate one of said elements towards the other to print, an electro-magnet to return the actuatable element, an electric circuit for said electro-magnet, a normally open switch in said circuit operable by the actuatable element to close said switch to energize the electro-magnet to return the operable element, means to lock the actuatable element in its returned position, and means operable by the key-levers to actuate the locking means to release the actuatable element so that it may be 70 actuated by said spring.

4. In a typewriting machine, the combination 75 of two co-operating elements, namely, a hammer and an anvil, a type shuttle associated with said elements, key-levers, a spring under the control of said key-levers to actuate one of said ele-

ments towards the other to print, an electro-magnet to return the actuatable element, an electric circuit for said electro-magnet, a normally open switch in said circuit operable by the actuatable element to close said switch to energize the electro-magnet to return the operable element, means operable by the actuatable element to initiate the closing operation of the switch, and means to complete the closing operation of the switch.

5. In a typewriting machine, the combination of two co-operating elements, namely, a hammer and an anvil, a type shuttle associated with said elements, key-levers, a spring under the control of said key-levers to actuate one of said elements towards the other to print, an electro-magnet to return the actuatable element, an electric circuit for said electro-magnet, a normally open switch in said circuit operable by the actuatable element to close said switch to energize the electro-magnet to return the operable element, means operable by the actuatable element to retard the closing of the switch to insure printing by the two co-operating elements before the return of the actuatable element is effected.

6. In a typewriting machine, the combination of two co-operating elements, namely, a hammer and an anvil, a type shuttle associated with said elements, key-levers, a spring under the control of said key-levers to actuate one of said elements towards the other to print, an electro-magnet to return the actuatable element, an electric circuit for said electro-magnet, a normally open switch in said circuit operable by the actuatable element to close said switch to energize the electro-magnet to return the operable element, said switch being operable by and upon the return stroke of the actuatable element, and a latch whereby the actuatable element may be locked in its returned position before the switch is completely 105 opened.

7. In a typewriting machine, the combination of two co-operating elements, namely, a hammer and an anvil, a type shuttle associated with said elements, key-levers, a spring under the control 110 of said key-levers to actuate one of said elements towards the other to print, an electro-magnet to return the actuatable element, an electric-circuit for said electro-magnet, a normally open switch in said circuit operable by the actuatable element 115 to close said switch to energize the electro-magnet to return the operable element, switch actuating means operable by the actuatable element, and means to further actuate the switch 120 actuating means to thereby open the switch after 130 the actuatable element has been completely restored.

8. In a typewriting machine, the combination of two co-operating elements, namely, a hammer and an anvil, a type shuttle associated with said 135 elements, key-levers, a spring under the control of said key-levers to actuate one of said elements towards the other to print, an electro-magnet to return the actuatable element, an electric circuit for said electro-magnet, a normally open switch in said circuit operable by the actuatable element to close said switch to energize the electro-magnet to return the actuatable element, switch actuating means operable by the actuatable 140 element to start the closing operation of said switch, and a device to further operate the switch 145 actuating means to close the switch to effect energization of the electro-magnet after printing to restore the actuatable element, and a latch to lock the actuatable element in its returned position, said switch actuating means being also operable by 150

- the actuatable element during the initial part of its return movement, said device being effective to further actuate the switch actuating means to open said switch, after the actuatable element has 5 been latched, to de-energize the electro-magnet. 9. In a typewriting machine, the combination of two co-operating elements, namely, a hammer and an anvil, a type shuttle associated with said elements, key-levers, means under the control of 10 said key-levers to actuate one of said elements to effect printing, an electro-magnet, means operable by the electro-magnet to restore the actuatable element, an electric circuit for said electro-magnet, said switch including a movable member, 15 means associated with said movable member tending to retard its operation, resilient means operable by the actuatable element to initiate the operation of said movable element, and means to complete the operation of the movable member to 20 close said switch, and thus effect energization of the electro-magnet to restore the hammer. 10. In a typewriting machine, the combination of two co-operating elements, namely, a hammer and an anvil, a type shuttle associated with said 25 elements, whereby the printing may be effected, an electro-magnet connected to actuate one of said elements, an electric circuit for said electro-magnet, a switch in said circuit whereby the electrical condition of said electro-magnet may be 30 altered, resilient means operable by the actuatable element to initiate the operation of said switch, means to retard the operation of said switch, and means to complete the operation of said switch after the complete operation of the actuatable 35 element. 11. In a typewriting machine, the combination of printing instrumentalities including a hammer, a spring to actuate said hammer, means to restore said hammer, a latch to hold said hammer in 40 normal position, key levers, a universal bar operable by said key-levers, means operable by the universal bar to actuate said latch to release said hammer, the latch actuating means when actuated through a predetermined distance disengaging 45 the latch, and means to restore the latch after such disengagement so as to be ready to engage the hammer when the latter is returned to normal. 12. In a typewriting machine, the combination 50 of printing instrumentalities including a hammer, a spring to actuate said hammer, means to restore said hammer, a latch to hold said hammer in normal position, key levers, a universal bar operable by said key-levers, means operable by 55 the universal bar to actuate said latch to release said hammer, the last named means disengaging the latch when actuated through a predetermined distance, and means to restore the latch so as to be ready to engage the hammer when the latter is returned to normal, the latch releasing means including a yieldable element to permit re-engagement of the latch releasing means with 60 said latch. 13. In a typewriting machine, the combination 65 of two co-operating elements, namely, a hammer and an anvil, a type shuttle associated with said elements, key-levers, means under the control of said key-levers to actuate one of said elements 70 towards the other to print, an electro-magnet to restore the actuatable element, a switch which may be closed to effect energization of the electro-magnet, said switch being operable by the actuatable element while the latter is moving to 75 its printing position, and means to delay the closing of the switch until the printing has been effected. 14. In a typewriting machine, the combination of a carriage, carriage propelling means, printing instrumentalities including two co-operating elements, namely a stationary element and an actuatable element, key-levers, a type carrier between the two co-operating elements, means operable by the key-levers to effect the setting of the type carrier, power means, means operable by the key-levers to render said power means effective to actuate the operable element of the printing instrumentalities, an electro-magnet, an electric circuit for said electro-magnet, a normally open switch in said circuit, and means operable by said key-levers to effect the closing of said switch, said electro-magnet being also effective to energize the power means for the actuatable element of the printing instrumentalities while said operable element is being returned to normal. 80 85 90 95 15. In a typewriting machine, the combination of printing instrumentalities including two co-operating elements, namely a stationary element and an actuatable element, key-levers, a settable type carrier between said co-operating elements, means operable by the key-levers to set the type carrier, power means, means operable by the key-levers to render said power means effective to operate said actuatable element, an electro-magnet, an electric circuit for the electro-magnet, a normally open switch in said circuit, means operable by said key-levers to initiate the closing of said switch, and means to retard the closing of the switch so as to insure printing before 100 105 110 115 120 125 130 135 140 145 the solenoid becomes effective to return said actuatable element. 16. In a typewriting machine, the combination of means including a selectively settable type carrier, a hammer to co-operate therewith, key-levers, power means to actuate the hammer, means operable by the key-levers to render the power means effective, an electro-magnet to return said hammer to normal, an electric circuit for the electro-magnet, a normally open switch in said circuit, and means to effect the closing of said switch to energize the electro-magnet to return said hammer. 17. In a typewriting machine, the combination of means including a selectively settable type carrier, a hammer to co-operate therewith, key-levers, power means to actuate the hammer, means operable by the key-levers to render the power means effective, an electro-magnet to return said hammer to normal, an electric circuit for the electro-magnet, a normally open switch in said circuit, means to effect the closing of said switch to return the hammer by said electro-magnet, and means to delay the closing of the switch to insure printing of said hammer before 130 135 140 145 the solenoid starts to return it. 18. In a typewriting machine, the combination of printing instrumentalities including two co-operating elements, namely a stationary element and an actuatable element, key-levers, a type carrier between the co-operating elements, means operable by the key-levers to effect the setting of the type carrier, power means to operate said actuatable element, means operable by the key-levers to render the power means effective, electrically operated means to return the actuatable element to normal, means to effect the operation of the electrically operated means, and means to delay the operation of the electrically operated means until the printing operation is completed. 150

19. In a typewriting machine, the combination of printing instrumentalities including two co-operating elements, namely a stationary element and an actuatable element, key-levers, a type carrier between the co-operating elements, means operable by the key-levers to effect the setting of the type carrier, power means to operate said actuatable element, means operable by the key-levers to render the power means effective, electrically operated means to return the actuatable element to normal, controlling means for the electrically operated means by which it may be rendered ineffective, means to initiate the operation of the controlling means, and means to delay the operation of the controlling means so as to insure the complete return movement of the actuatable element by the electrically operated means before it is rendered ineffective. 80
20. In a typewriting machine, the combination of printing instrumentalities including two co-operating elements, namely a stationary element and an actuatable element, a selectively settable type carrier between the co-operating elements, power means to operate said actuatable element, means to render the power means effective, power means including a solenoid to return the actuatable element to normal, controlling means for the solenoid, said controlling means being operable by the actuatable element on its effective movement to render the solenoid effective to return the actuatable element, said controlling means being operable by the actuatable element on its return stroke to render the solenoid ineffective, and means to retard the operation of the controlling means so that the actuatable element may be completely returned before the solenoid is rendered effective and to insure the complete return of the actuatable element before the solenoid is rendered ineffective. 85
21. In a typewriting machine, the combination of printing instrumentalities including two co-operating elements, namely a stationary element and an actuatable element, a selectively settable type carrier between the co-operating elements, a spring to operate said actuatable element, a latch to normally hold the actuatable element against the action of said spring, means to release the actuatable element from the latch, an electrically operated device to return said actuatable element to normal, controlling means for said electrically operated device, means to actuate the controlling means to render said electrically operated device effective and ineffective, and means co-operating with the controlling means whereby the electrically operated device is maintained effective until the actuatable element has been returned to the latch against the action of said spring. 90
22. In a typewriting machine, the combination of printing instrumentalities including two co-operating elements, namely a stationary element and an actuatable element, a selectively settable type carrier associated with said elements, power means to operate said actuatable element, means to render the power means effective, an electric device to return the actuatable element, a pivoted switch element to render the device effective and ineffective, a stop for the switch element, a detent to hold the switch element against said stop, and a resilient device operable by said actuatable element to start the closing operation of said switch element and to gradually overcome the holding action of the detent, the latter becoming finally effective to complete the operation of the switch element to close it after the printing operation and thus effect the operation of the electric device to return the actuatable element. 95
23. In a typewriting machine, the combination of printing instrumentalities including two co-operating elements, namely a stationary element and an actuatable element, a selectively settable type carrier associated with said elements, power means to operate said actuatable element, means to render the power means effective, an electric device to return the actuatable element, a pivoted switch element to render the device effective and ineffective, means to actuate said switch to render the electric device effective to return the actuatable element to normal against the action of the power means, means to hold the actuatable element in its returned position, resilient means operable by the actuatable element to start the opening operation of the switch element, and a detent tending to retard the operation of said switch so as to insure the return of the actuatable element to the holding means before the switch is opened, the resilient device being effective to gradually overcome the retarding action of said detent, the latter becoming finally effective to open said switch to render the electric device ineffective. 100
24. In a typewriting machine, the combination of printing instrumentalities including two co-operating elements, namely a stationary element and an actuatable element, a selectively settable type carrier associated with said elements, power means to operate the actuatable element in one direction, an electric device to operate the actuatable element in the opposite direction, a pivoted switch for said electric device, resilient means operable by the actuatable element to start the operation of said switch, means tending to retard the operation of said switch to insure the completion of the operation of the actuatable element before it is operated in the opposite direction, the retarding means becoming finally effective to complete the operation of said switch. 105
25. In a typewriting machine, the combination of printing instrumentalities including two co-operating elements, namely a stationary element and an actuatable element, a selectively settable type carrier associated with said elements, power means to operate the actuatable element in one direction, an electric device to operate the actuatable device in the opposite direction, a pivoted switch for said electric device operable by the actuatable element to start the operation of said switch, means tending to retard the operation of said switch to insure the completion of the operation of the actuatable element before it is operated in the opposite direction, and means to overcome the action of the retarding means. 110
